TELEVISION CABINET LIGHTING UNIT

Marcel Claveau, St. Antoine des Laurentides, Quebec,
Canada

Application May 7, 1954, Serial No. 30,380

Term of patent 14 years

(Cl. D48—20)

To all whom it may concern:

Be it known that I, Marcel Claveau, a Canadian citizen, resident of St. Antoine des Laurentides, Terrebonne County, in the Province of Quebec, Canada, have invented a new, original, and ornamental Design for a Television Cabinet Lighting Unit, of which the following is a specification, reference being had to the accompanying drawing, forming part thereof.

The single drawing figure is a perspective view of a television cabinet lighting unit showing my new design.

The broken lines shown in said drawing are for illustrative purposes only.

I claim:

The ornamental design for a television cabinet lighting unit, as shown.
